CYLINDER CHECK MECHANISM FOR
DUPLICATING MACHINES

Ronald Max Ford and George Thomas Butler,
Sparkbrook, Birmingham, England; said Butler
assignor to Frank R. Ford Limited, Sparkbrook,
Birmingham, England, a British company

Application April 27, 1950, Serial No. 158,381
In Great Britain May 7, 1949

2 Claims. (Cl. 101—245)

1

This invention relates to duplicating machines of the kind in which a copy sheet and a master sheet bearing in reversed script the matter to be reproduced are passed in pressure contact between a cylinder which carries the master sheet and a pressure roller, the copy sheet being moistened before being brought into contact with the master sheet.

In machines of this kind it is usual to provide the cylinder with a shaft and to mount this shaft in bearings in opposite side members of a frame, and it is known to provide on the end of the cylinder and on the frame co-operating check members for checking the rotary movement of the cylinder at a certain position in each revolution thereof to ensure that when a copy sheet is fed in the leading end of the master sheet is in the correct position relative to the leading end of the copy sheet, so that the matter on the master sheet will be reproduced on the copy sheet in the desired position in relation to the end of the copy sheet.

Such means have usually consisted of a cam or disc on the end of the cylinder, said cam or disc having a notch in its periphery, and the other check member taking the form of a lever pivoted to the frame and pressed by a spring against the periphery of the cam or disc, the lever having a projection which engages the notch when the cylinder is in the check position. With this arrangement, as the lever is always in pressure contact with the periphery of the cam or disc, wear takes place on these parts and further wear takes place on the projection on the lever and in the notch in the periphery of the disc or cam.

The object of the present invention is to provide an improved construction.

According to one feature of the present invention one of the check members is formed as a spring-loaded lever which normally engages a stop, which lever is out of contact with the other check member during the major part of the rotation of the cylinder and is engaged thereby only at and near the check position of the cylinder.

According to another feature of the present invention one of the check members is formed as a roller mounted for rotation.

The lever may be pivoted to the end of the cylinder, and the roller may be mounted for rotation on a pin projecting inwardly from the frame, the arrangement being such that pivotal movement of the lever in an inward direction towards the axis is limited by a stop, but as the

2

cylinder revolves the inner edge of the lever comes into contact with the roller near the check position, and at the check position a notch in the lever engages the roller so as to check the rotary motion of the cylinder without positively preventing it. Continued pressure to rotate the cylinder causes the lever to move away from the roller, after which the lever again makes an inward movement towards the axis of the cylinder, which is limited by a stop.

The invention is illustrated in the accompanying drawings wherein:

Figure 1 is a view in side elevation of a duplicating machine according to the present invention.

Figure 2 is a part section on the line 2—2 in Figure 1.

Figure 3 is a section on the line 3—3 in Figure 2.

Figure 4 is a section on the line 4—4 in Figure 2.

In the construction shown in the accompanying drawings the cylinder 10 is made of a length of tube having end plates 11 which are secured in the tube at a short distance from each end. A spindle 12 extends through the cylinder, or may be made in two parts one attached to each end plate at the centre, and the ends of this spindle, or these spindles, engage in bearings 13 which project inwardly from the side members 14 of the frame of the machine. The said bearings 13 are formed on or attached to a plate secured to the inner surface of the side member 14 of the frame, and this plate may be of circular or other form and carries a pin 15 projecting parallel to the said bearing, and on the pin is mounted a roller 16. This pin 15 and roller 16 are mounted a suitable distance away from the actual bearing.

Pivoted to one of the end plates 11 of the cylinder 10 is a lever 17. This lever is pivoted at one end on an axis 18 parallel to the axis of the cylinder, and at the opposite end the lever 17 engages a stop pin 19 fixed to the end plate 11 of the cylinder. The lever 17 is thus housed within the cavity formed by the projecting end of the tube forming the cylinder 10.

On its inner edge at a suitable position the lever 17 is provided with a V-shaped notch 20, and operating between the back edge of the lever and the tube forming the cylinder 10 is a compression spring 21, so that the lever is spring-loaded towards the axis of the cylinder, but such inward movement is limited by the stop.

The cylinder 20 may be rotated by means of

a handle 22 and moistening means as generally indicated at 23 are provided for moistening the copy sheet 24 which is fed from a feed table 25. Pressure roller 26 is provided, supported and mounted for adjustment by means which are more specifically described in our copending application Serial No. 158,382 filed herewith.

When the cylinder 10 is in position in the machine and is rotated the lever is out of contact with the roller for the major part of the revolution of the cylinder, but as the cylinder approaches the check position the roller engages the inner edge of the lever, and at the check position the roller is engaged by the V-shaped notch in the lever. Thus, the rotary motion of the cylinder is checked, but the cylinder is not positively locked and rotation can be continued by exercising a reasonable amount of pressure on the usual handle provided for rotating the cylinder.

When this is done the lever rides clear of the roller, making a pivotal movement away from the axis of the cylinder as it does so. When the lever has moved away from the roller it moves back into its normal position under the influence of the spring.

What we claim then is:

1. In a duplicating machine of the kind specified, a frame, a cylinder for carrying a master sheet rotatably mounted in said frame, said cylinder having an end face and being extended beyond the end face to provide a recess at the end of the cylinder, co-operating check members on the cylinder and on the frame for checking the rotary movement of the cylinder during each revolution, said co-operating check members comprising a lever, having a notch in one side thereof pivotally mounted at its one end on the said end face on an axis parallel to the axis of the cylinder, a stop on the end face of the cylinder, normally engaged by the other end of said lever to prevent inward pivotal movement of the lever towards the axis of the cylinder, spring means mounted on the said end face urging said lever so as to engage said stop, said lever, stop and spring means being all housed within the said recess at the end of the cylinder, and a check member mounted on the adjacent part of the machine frame, projecting into

said recess and co-operating with the notch in said lever, for checking rotation of the cylinder at a certain position in each revolution, said lever being out of contact with said check member during the major part of a revolution and being engaged thereby at and near the check position.

2. In a duplicating machine of the kind specified, a frame, a cylinder for carrying a master sheet rotatably mounted in said frame, said cylinder having an end face and being extended beyond the end face to provide a recess at the end of the cylinder, co-operating check members on the cylinder and on the frame for checking the rotary movement of the cylinder during each revolution, said co-operating check members comprising a lever pivotally mounted at its one end on the said end face on an axis parallel to the axis of the cylinder, a stop on the end face of the cylinder normally engaged by the other end of said lever to prevent inward pivotal movement of the lever towards the axis of the cylinder, a spring acting between said lever and the inside of the cylinder urging said lever so as to engage the stop, said lever, stop and spring being all housed within the said recess at the end of the cylinder, a pin projecting inwardly from the frame into said recess and a roller mounted for rotation on said pin, cooperating with said lever, for checking rotation of the cylinder at a certain position in each revolution, said lever being out of contact with said roller during the major part of a revolution and being engaged thereby at and near the check position.
